UNITED STATES PATENT OFFICE.

WILLIAM J. KELLY, OF CLINTON, IOWA, ASSIGNOR TO LOVELL MANUFACTURING COMPANY, OF ERIE, PENNSYLVANIA, A CORPORATION OF PENNSYLVANIA.

CLOTHES-WRINGER.

1,162,492.

Specification of Letters Patent. Patented Nov. 30, 1915.

Application filed November 6, 1912. Serial No. 729,854.

To all whom it may concern:

Be it known that I, WILLIAM J. KELLY, a citizen of the United States, residing at Clinton, in the county of Clinton and State of Iowa, have invented new and useful Improvements in Clothes-Wringers, of which the following is a specification.

This invention relates to clothes wringers and particularly that type of wringers having a pressure rail or bar at the top portion with adjusting means to hold the rollers in firm associated relation or in such close position relatively to each other as to render the wringing operation effective.

The primary object of the invention is to provide a clothes wringer with means for quickly releasing the pressure on the upper roller for the purpose of loosening the latter in order that an operator may readily extricate the hand used in feeding the clothes from injurious engagement with the rollers and also to facilitate the release of articles of clothing from the rollers that may be wound around the latter, especially articles of fine material.

The invention is adapted for use either on hand wringers or on power operated wringers used in connection with other laundry machinery, and in power operated wringers there is always considerable danger to the operator in feeding the machine in that the fingers of the hand are liable to be drawn in between the rollers and crushed or mashed, and, furthermore, in operating power wringers loss of fine pieces or articles often ensues, especially when made from some thin material in view of the fact that the goods being of light weight wrap around the rollers and wind so tight that it is almost impossible to release them and if a pulling strain is exerted on such fine articles to effect a release under the conditions noted, the articles are torn or otherwise injured. The release attachment embodying the present features of the invention has been devised to overcome these disadvantages, both in hand-operated and power wringers.

In the drawings: Figure 1 is a perspective view of a wringer embodying the features of the invention. Fig. 2 is a longitudinal vertical section through a portion of the wringer. Fig. 3 is an elevation of the portion of the wringer showing parts broken away and illustrating the clamping rail or bar in released position.

The numeral 5 designates the lower roller and 6 the upper roller of the pair of rollers as ordinarily used in a clothes wringer and mounted for rotation in suitable bearings provided in the upright frame posts or side stiles 7 and 8, the said posts being slotted as at 9 and the rollers 5 and 6 having their spindles 10 extending into the slots and the upper roller supporting compression springs 11 to yieldingly dispose the said upper roller above and in close association with the lower roller. In the slots 9 the opposite extremities of a pressure bar 12 are movably mounted, and on the opposite ends of this bar are metallic contact plates 13. It will be understood that the compression springs 11 are located at opposite ends of the wringer and the pressure bar has the contact strips or plates 13 projected beyond the ends of the bar and provided with depending studs 14 over which the upper ends of the springs 11 are fitted, as clearly shown by Fig. 2. The lower ends of the springs 11 are fitted over posts 15 projecting upwardly from saddle bearings 16 engaging the extremities of the spindles 10 of the upper roller 6, the spindles 10 of the lower roller having opposite extremities resting upon metal bearings 17 at the bottoms of the slots 9. The construction as just described is well known in the art and may be modified, or any other analogous organization may be adopted, and in the present form of wringer the usual clamping rail 18 is employed and is hinged at one end as at 19 and has the other end free to open, the said rail carrying clamping or adjusting screws 20, the lower ends of the screws being adapted to engage the strips or plates 13 to regulate the tension on the roller 6 through the springs 11.

A releasing means for the clamping rail 18 is embodied in the wringer and consists of an angle plate 21 secured over the free end of the said rail 18 and depending below the same and formed with a slot 22, the lower extremity of the angle plate or hinge member 21 being bifurcated to form the said slot and provide knuckles 23, and in this bifurcated portion of the angle plate or hinge member 21 the upper end of a latch 24 is pivotally mounted. The latch 24 embodies a head 25 and a notch 26 at the lower terminal of the head and a depending handle 27. The notch 26 has a base wall 28 forming a shoulder which runs off through a curved

- corner 29 into the inner edge of the depending handle 27, and the head 25 gradually curves down to the notch 26 with sufficient clearance to facilitate engagement of the 5 latch with and release of the said latch from an angular catch plate 30 secured at a suitable elevation on the one upright or side stile 7 and extending fully across the slot or opening 9, as clearly shown by Fig. 1.
- 10 Engaging the extremity of the rail or bar 18 opposite that to which the latch 24 is connected is a spring 31 having an arm 32 attached to the end of the rail or bar 18 and a coil 33 suitably engaging the pin 34 of a 15 hinge 35, the said spring also having a depending arm 36 secured to the outer edge portion of the adjacent upright or side stile 8. The function of this spring 31 is to exert upward pressure on the clamping rail and to 20 add to the pressure exerted by springs 11 to quickly throw the rail or bar 18 upwardly when released by the latch 24.
- The wringer is arranged in normal condition for operation by pressing downwardly on the rail 18 and drawing the latch 24 inwardly and causing the notch 26 to engage the catch 30, the shoulder 28 of the 25 latch bearing against the under part of the catch, as clearly shown by Fig. 2. When 30 it is desired to release the rail 18 and relax the pressure of the upper roller 6, the latch 24 is released by drawing outwardly on the depending handle 27 thereof to disengage the shoulder 28 from the catch 30, and im- 35 mediately the springs throw the rail or bar 18 upwardly and release the pressure or compression springs 11 to permit the upper roller 6 to be raised sufficiently from the lower roller 5 to release any article that may 40 become wound around the rollers, or in the event of accident to the hand of the operator permit the latter to withdraw the hand. The wringer may be afterward reset by a 45 very simple operation to bring the roller 6 in close association with the roller 5. It will be seen that the latch 24 may be readily manipulated to release the rail 18 and consequently slacken the springs 11, and said catch is in a position most effective for 50 quickly operating the same. It will be observed that in this construction of wringer the clamping rail occupies the position ordinarily occupied by similar devices and is also brought back or closed down in the 55 same fixed position and the adjustment of the springs 11 is effected by the adjusting screws 20 carried by the rail. It will also be seen that the hinge for the clamping rail is offset with relation to the side stile to which 60 it is attached and the adjacent spring. This arrangement is particularly desirable in wringer structures wherein the springs are

mounted in slots in the side stiles as in the present instance.

A further advantage of the improved 65 wringer attachment is that the roller 6 may be readily released in case an operator should overload the wringer with a very heavy piece of goods and interfere with the free operation of the rollers and stall the 70 motor for driving the wringer. If an electric type of motor is used as the power means, burning out of the said motor will be prevented under the stalling conditions just explained by the quick release of the 75 roller 6. A still further advantage in the reinforcement of the wringer structure generally results in that the catch piece braces the frame posts or side stiles 7 and 8 at one 80 side and strengthens the said posts or side stiles in view of the necessity of cutting out the wood to make room for the spring, and at the opposite side the lower portion of the hinge 35 serves as a strengthening means.

The improved wringer attachment will be 85 found exceptionally advantageous for the purpose for which it has been devised, and the same may be applied to wringers now in use at a comparatively small expense and without disorganizing such wringers. 90

It will be understood that the proportions and dimensions of the several parts may be modified at will without departing from the spirit of the invention.

What is claimed is:

1. In a clothes wringer, the combination of a frame having side stiles, wringing rollers mounted in said stiles, spring pressure means coacting with said rollers, an upper clamping rail hinged at one end and having 100 a fixed location with relation to the stiles when closed down, adjustable devices carried by the rail to coöperate with and regulate the tension of the spring pressure means, and means for detachably locking the rail 105 in depressed position with the side stiles.

2. In a clothes wringer, the combination of a frame having side stiles with slots, wringing rollers mounted between the stiles, springs coacting with the rollers and disposed in the slots of the side stiles, an upper clamping rail having a hinge connection offset with relation to the adjacent spring, adjusting devices carried by the rail to coöperate with and regulate the tension of 115 the springs, and means for detachably locking the rail with the stiles in closed position.

In testimony whereof I have hereunto set my hand in presence of two subscribing witnesses.

WILLIAM J. KELLY.

Witnesses:

M. A. ANDERSON,
G. D. KEEFE.
